Frederick J. Larson
ATTORNEY.

UNITED STATES PATENT OFFICE

WALTER L. RUTKOWSKI, OF ST. LOUIS, MISSOURI, ASSIGNOR TO R. C. CAN COMPANY,
OF ST. LOUIS, MISSOURI, A CORPORATION OF MISSOURI

WHISTLE

Application filed March 5, 1928. Serial No. 259,339.

My invention relates to whistles, and, has for its particular object to provide a whistle for producing two different notes, or sounds which blend and result in a single blast when the whistle is blown.

A further object of the invention is to provide a hollow whistle body formed from a single piece of metal which is provided with two sound outlet openings and within which body there is positioned a reed partition having two deflectors in register with the forward edges of the outlet openings and said deflectors being formed by folding spaced sections of the partitions by means 15 of a die operation.

A still further object of the invention is to provide a whistle body from a single piece of metal, so blanked as to provide a hollow circular sound chamber body section when 20 folded midway its length and to provide a shallow tubular mouth piece section, both of which folded body sections are clinched or crimped together at their marginal edges by overlapping the edge of one half of the 25 body upon the edge of the other half of the body.

A still further object of the invention is the positioning of the reed partition between the marginal edges of the two halves of the 30 body when folded to prevent displacement thereof when the marginal edge of one half of the body is clinched over the marginal edge of the other half of the body.

A still further object of the invention is 35 the provision of a whistle which possesses advantages in points of simplicity and efficiency, and, at the same time proves itself comparatively inexpensive in cost of manufacture.

With the above and other objects in view, 40 the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a plan view of the inside of the

body before it has been folded and after it has been blanked and shaped.

Fig. 2, is a side elevation thereof.

Fig. 3, is a plan view of the reed partition in its blanked form.

Fig. 4, is a plan view of the reed partition after it has the deflectors formed as an integral part thereof.

Fig. 5, is a side elevation thereof.

Fig. 6, is a longitudinal sectional elevation 60 of the whistle after it has been assembled.

Fig. 7, is a top plan view of the whistle.

Fig. 8, is a sectional elevation taken on line 8—8 of Fig. 7.

In carrying out the aim of my invention, I 65 employ a whistle body made from a single piece of metal so shaped as to form two similar body sections A and B joined together by means of a connecting strip, as at 1. The body sections A and B are provided with the 70 flat marginal flanges 2 and 3, respectively and with the circular dished sound box portions 4 and 5, respectively. The body sections A and B are further provided with the longitudinally channelled neck portions 6 and 7, 75 respectively, and the body section B only is provided with a lip 8 which is a termination of the flat marginal flange 3 of body section B. The body sections A and B are further provided with the sound outlet openings 9 and 10, respectively. The sound outlet openings 9 and 10 are in the longitudinally channelled neck portions of the body sections A and B in advance of the circular dished portions 4 and 5 thereof, as clearly shown in Figs. 80 1 and 2.

The reed section C of the whistle is in the form of a single piece of thin flat metal blanked out in the form shown in Fig. 3 and consists of a circular head portion 11 and a 90 neck portion 12 and which neck portion 12 has its side edges each provided with the cut-out portions 13 and 14. The neck portion 12 is then pressed outwardly in V-shaped form between the cutout portions 13 to provide a 95 deflector 15 and also pressed outwardly in V-shaped form in an opposite direction between the cutout portions 14 to provide a deflector 16, as clearly shown in Fig. 5.

To assemble the whistle after the body 100

thereof and the reed have been formed, the reed section C is positioned upon the flat marginal flange 3 of body section B and then the body section A is folded, as at 17 at the connecting strip 1 so that the flat marginal flanges 2 thereof will be in contact with the reed section 13 and lie between the flat marginal flanges 2 and 3 of the body sections A and B. When this has been accomplished, the lip 8 of body section B is clamped, or crimped over the flat marginal flange 2 of body section A to firmly hold the reed section C from displacement between the body sections A and B, as clearly shown in Figs. 6, 7 and 8.

When the parts have been assembled, it will be apparent from Fig. 6 of the drawings that the body sections of the whistle form a sound box D at one end thereof which has connection with the throat of the whistle, as shown in Fig. 6. It will be here observed that the reed section C acts as a partition for the sound box D and the throat E and provides two air passages designated 18 and 19 in the throat section of the whistle which 25 communicates with two sound chambers 20 and 21 of the sound box section D, as clearly shown in Fig. 6. It will be further observed that the deflector 15 is disposed in the air passage 18 adjacent the sound outlet opening 9 and that the deflector 16 is disposed in the air passage 19 adjacent the sound outlet opening 10, thereby providing means for producing a two tone whistle. The throat or neck portion of the whistle is preferably, al- 35 though not necessarily slightly tapered, as shown in Fig. 6, so that it will be a little larger in diameter at its outer end than at its inner end and in this case the deflector 15 is of less height than deflector 16, as is manifest. The 40 whistle is so formed, as will be apparent from Figs. 6 and 8 that it is elliptical in cross-section.

The body section and the reed section each being formed from a single piece of metal enables me to produce a two tone whistle at a low cost of manufacture with no unnecessary parts to be handled in the assembly of the device.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. A two tone whistle comprising a tubular body having a sound box section and a throat section composed of two similar body sections folded midway their ends and having sound outlet openings therein, a reed

member disposed between the body sections sub-dividing the body into two compartments and deflectors formed on said reed member, said deflectors being characterized by portions pressed from said reed member extending in opposite directions and disposed adjacent said outlet openings in the body sections. 70

2. A two tone whistle comprising two similar body sections each having a sound outlet opening therein folded midway their ends to form a tubular body which is elliptical in cross-section, a reed member disposed between said two body sections, means for clamping the two body sections together at their marginal edges to retain the reed member against displacement and opposed directed deflectors formed on the reed member by depressing portions of the reed member in V-shaped formation, said deflectors having their apices disposed opposite the forward edges of the sound outlet openings. 75 80 85

3. In a two tone whistle comprising a single piece of metal blanked to form two like body sections each having a sound outlet opening, said body sections being provided at one end with circular depressed portions and longitudinally channeled portions communicating with the circular depressed portions, a flat marginal flange for each body section, a lip terminating from the flange of one of the body sections, said body sections being folded midway their ends, a reed member disposed between the two body sections and in contact with the flat marginal flanges thereof for sub-dividing the body into two compartments, said lip being crimped into contact with the marginal flange opposite the flange from which it terminates for retaining said reed member against displacement between the two body sections and a pair of V-shaped deflectors formed integral with the reed member and disposed with their apices in alignment with the forward edges of sound outlet openings. 90 95 100 105 110

4. A reed member for two tone whistles comprising a metallic member having a circular disc shaped end terminating in a relatively narrow neck extension and a pair of deflectors formed on said neck extension, said deflectors being characterized by portions pressed from said neck extension and extending in opposite directions. 115

5. A reed member for two tone whistles comprising a flat circular metallic head portion, a narrowed neck extension directed therefrom and integral therewith and spaced V-shaped deflectors formed on said neck extension, said deflectors being directed from opposite faces of the neck extension. 120 125

In testimony whereof I have hereunto affixed my signature.

WALTER L. RUTKOWSKI.
